UNITED STATES PATENT OFFICE

2,208,425

RAILWAY TRUCK

Ole K. Kjolseth, Erie, Pa., assignor to General
Electric Company, a corporation of New York

Application February 7, 1939, Serial No. 255,080

12 Claims. (Cl. 105—182)

My invention relates to trucks for railway vehicles.

An object of my invention is to provide an improved railway truck and bolster supporting arrangement for such a truck.

Another object of my invention is to provide an improved railway truck having a floating bolster and a lateral restraint device for such a bolster.

Further objects and advantages of my invention will become apparent and my invention will be better understood from the following description referring to the accompanying drawing, and the features of novelty which characterize my invention will be pointed out with particularity in the claims annexed to and forming part of this specification.

In the drawing, Fig. 1 is a side elevation of a truck embodying my invention, partly broken away to show the main bolster supporting arrangement; Fig. 2 is a partial plan view of the truck shown in Fig. 1, partly broken away to illustrate the relative arrangement of the side frames, the main bolster, and the floating bolster supporting arrangements; Fig. 3 is a sectional view taken along line 3—3 of Fig. 2; Fig. 4 is a partial sectional view taken along line 4—4 of Fig. 2; Fig. 5 is a partial sectional view similar to Fig. 4 illustrating another embodiment of my improved side bearing arrangement between the floating bolster and the main bolster; and Fig. 6 is a partial sectional view similar to Fig. 4 of another embodiment of my invention illustrating another type of floating bolster lateral restraint device and side bearing.

Referring to the drawing, I have shown a truck for railway vehicles having a pair of wheels 10 mounted on each of a pair of axles 11 arranged to support longitudinally extending side frames 12. These side frames are arranged on each side of the truck as equalizers extending between the axles, with each end of the side frame formed as a journal box 13 arranged about an axle journal bearing on the axles 11. A main bolster 14 extends transversely between the two side frames 12 and is provided at each end thereof with a longitudinally extending portion 15 formed with downwardly extending arms 16 which project into openings 17 formed in the side frames 12 adjacent the journal boxes 13. Upwardly extending bearings 18 are provided on each side of the openings 17 in the side frames adjacent the arms 16, and these bolster arms 16 are arranged to engage the bearings 18 to transmit lateral forces between the main bolster 14 and the side frames 12.

In railway trucks, it is necessary to transmit lateral, vertical, and longitudinal forces from the bolster to the truck side frames, and from thence to the truck axles. In order to support resiliently the bolster 14 and to transmit vertical forces be-

tween the bolster and the side frames, I provide a dual resilient support for the main bolster 14 on the side frames 12. This resilient supporting arrangement includes spring seats 19 formed on each side of the middle of the side frames and arranged to support a plurality of resilient coil springs 20 which engage spring seats 21 formed on the under side of the longitudinally extending portions 15 at each end of the bolster 14. These provide a relatively low resistance resilient support for the bolster and allow for a certain amount of longitudinal tilting of the main bolster 14 with respect to the side frames 12 and the axles 11. A relatively high resistance resilient support also is provided at each end of the main bolster 14 by a semi-elliptic leaf spring 22 which is pivotally suspended from the side frame 12 by a spring hanger 23 arranged at each end thereof and pivotally secured to the side frame 12 by a pivot pin 24. A downwardly extending arm 25 is formed on the end of the bolster 14 adjacent the transverse center thereof and extends downwardly into an opening 26 formed in the side frame 12. This arm 25 engages a spring strap 27 arranged about the central portion of the leaf spring 22. A limit pin 28 is secured in openings formed in bosses 29 on each side of the side frame 12 and extends through vertically extending slots 30 formed in the sides of the downwardly extending arm 25 to allow a predetermined limited amount of relative vertical movement between the bolster 14 and the side frames 12 and to limit this movement to a safe operating value.

Tractive and other longitudinal forces are transmitted between the main bolster 14 and the side frames through a longitudinally extending link member 31 arranged on each side of the truck and pivotally secured to the bolster by a pivot pin 32 rotatably mounted in bosses 33 formed on the bolster and pivotally secured at the other end thereof to the side frame 12 by a pivot pin 34 rotatably mounted in ears 35 formed on the side frame. This pair of pivotally secured links 31 allows a predetermined amount of relative vertical movement between the bolster 14 and the side frames 12 while providing a rigid longitudinal connection between these members. In order to provide a more easy riding truck construction, I provide a laterally movable floating bolster 36 having a center bearing 37 adapted to support a complementary vehicle center bearing 38 secured to a vehicle frame 39 for supporting the vehicle upon the truck. The vehicle is provided with conventional side bearings 40 which are arranged to engage complementary side bearings 41 formed on the floating bolster 36 to limit lateral swaying of the vehicle frame 39 with respect to the floating bolster 36 and the truck frame. In order resiliently to support the float-

ing bolster 36 and to transmit vertical forces between this bolster and the main bolster 14, I provide a plurality of nested resilient coil springs 42 which engage spring seats 43 formed on the main bolster 14 and spring seats 44 formed on the under side of the floating bolster 36. Tractive and other longitudinal forces are transmitted between the floating bolster and the main bolster through vertically extending bearings 45 formed 5 on each side of the floating bolster 36 which engage complementary vertically extending bearings 46 formed on the inner sides of a recess 47 formed in the main bolster 14, and in which the floating bolster 36 is arranged.

15 Lateral forces are transmitted between the floating bolster 36 and the main bolster 14 by vertically extending side bearings 48 formed on the ends of the bolster 36 and adapted to engage complementary vertically extending side bearings 49 at the ends of the recess 47 on the main bolster 14. These bearings 48 and 49 do not engage each other when the floating bolster is in its centered position and under these conditions, there are no lateral forces to be transmitted between the floating bolster and the main bolster. In order to provide for a slight amount of relative lateral movement between the floating bolster and the main bolster, a predetermined amount of clearance is provided between these bearings, and in order to prevent violent shocks and jars when the floating bolster 36 moves laterally and the bearings 48 and 49 come in contact, I provide a lateral restraint device which is adapted to restrain lateral movements of the floating bolster and to provide a vertically movable pivotal center about which a floating bolster may pivot or tilt. This restraint device includes a pair of vertically extending bearings 50 secured to the main bolster adjacent the longitudinal and transverse center 25 thereof and mounted on laterally and downwardly extending bracket arms 51 formed on the main bolster 14. A cooperating rocker device is secured to the floating bolster, and includes a rocker seat bearing plate 51' mounted on the under side 30 thereof and a downwardly extending rocker element 52 provided with a pair of semi-cylindrical rocker bearings 53 arranged to engage the rocker seats in the bearing plate 51'. The rocker 52 is provided with a roller 54 rotatably supported on a 35 pair of arms 55 by a pivot pin 56 and arranged to engage the two bearings 50 and to guide the rocker 52 about a vertically movable pivotal center corresponding to the axis of the pivot pin 56. In order resiliently to bias the rocker 52 into engagement 40 with the rocker bearing plate 51', I provide an upwardly extending rod 57, one end of which is pivotally secured by a pivot pin 58 to upwardly extending ears 59 formed adjacent the center of the upper side of the rocker 52, and bias the upper 45 end of the rod 57 away from the rocker 52 by a nest of coil springs 59'. These coil springs are arranged to be held in compression between a spring seat 60 formed in the center bearing 38 and a spring seat 61 which slidably engages the 50 upper end of the rod 57 and is secured thereon by nuts 62. In this manner, slight lateral movement of the floating bolster may take place and be cushioned by the lateral restraint device without engagement of the complementary side bearings 70 48 and 49. However, if the lateral and tilting or roll forces producing the lateral movement or tilting of the floating bolster become sufficiently great due to relatively large tilting or roll of the vehicle with respect to the trucks, these complementary side bearings are adapted to come in

contact and provide a fulcrum for the roll or tilt of the floating bolster with the vehicle frame. This will compress the springs 59' and dampen or restrain such movement and transmit the lateral forces between the floating bolster and the main bolster through these side bearings. In this manner, I provide an improved truck construction having a more quiet operating and easy riding supporting arrangement which provides for the cushioning of lateral and vertical forces which are transmitted between the truck frame and the center bearing supporting the vehicle, and at the same time, provide for the transmittal of vertical, lateral, and longitudinal forces between these elements of the truck.

Fig. 5 illustrates a modification of the complementary side bearings between the floating bolster 36 and the main bolster 14. In this arrangement, the main bolster is provided with a vertically extending bearing 63 mounted on a supporting bracket 64 formed on the main bolster 14 adjacent the longitudinal center thereof on the side of the recess 47. The floating bolster is provided with a complementary side bearing member including a crank 65 which is pivotally supported by a pivot pin 66 rotatably mounted in ears 67 formed on the end of the bolster. A roller 68 is rotatably mounted on a pivot pin 69 supported on one arm 70 of the crank 65, and this roller 68 is adapted to be resiliently biased into engagement with the bearing 63 by the other arm 71 of the crank 65. This arm 71 is biased in a clockwise direction, as shown in Fig. 5, by engagement with a vertically extending push rod 72 which slidably extends through an opening formed in the bolster 36 and is formed with a spring seat 73 arranged in engagement with the upper end of one of the coil springs 42 which support the floating bolster 36 on the main bolster 14. In this manner, I provide a more silent side bearing between the floating bolster and the main bolster, and also provide an additional damping arrangement for cushioning relative lateral displacements between the floating and main bolsters.

Fig. 6 shows another embodiment of my invention wherein the side bearings between the floating bolster and the main bolster include a roller 74 mounted on a pivot pin 75 rotatably supported by a vertically extending support and side bearing 76. The roller 74 is arranged in engagement with a bearing surface 77 mounted on a block 78 of resilient material, such as resilient rubber, secured to a supporting bracket 79 formed on the longitudinally extending portion 15 of the main bolster 14. The floating bolster in this arrangement is provided with a conventional center bearing plate 80 arranged to support a center bearing 81 secured to a vehicle frame 82. In this arrangement, the lateral restraint device comprises the vertically extending bearings 50 supported on the brackets 51, as in the construction shown in Figs. 1 to 4, inclusive, and the cooperating floating bolster member includes only a downwardly extending pair of arms 82' which rotatably support a roller 83 on a pivot pin 84 in engagement with the bearings 50. In this manner, the roller 83 provides a vertically movable pivotal center for the floating bolster about the center line of the pivot pin 84, and relative lateral motion and tilting of the floating bolster 36 is cushioned by the plurality of nested coil springs 42.

While I have illustrated and described various embodiments of my invention, which provide for the transmission of lateral, longitudinal, and vertical forces between the floating bolster and

the axles of a truck through the side frames thereof, modifications thereof will occur to those skilled in the art. I desire it to be understood, therefore, that my invention is not to be limited to the 5 particular arrangements disclosed, and I intend in the appended claims to cover all modifications which do not depart from the spirit and scope of my invention.

What I claim as new and desire to secure by 10 Letters Patent of the United States is:

1. A railway truck having side frames, a bolster extending transversely of said truck and having downwardly extending arms adapted to engage said side frames for transmitting lateral forces 15 between said bolster and said side frames, means for resiliently supporting said bolster on said side frames, means including a floating bolster for supporting a railway vehicle on said truck, means for resiliently supporting said floating bolster on said first-mentioned bolster, a lateral restraint device for said floating bolster including vertically extending bearings secured to said first-mentioned bolster adjacent the longitudinal and transverse center thereof, and means on said floating bolster arranged to engage said bearings for guiding said floating bolster about a vertically movable pivotal center.

2. A railway truck having side frames, a bolster extending transversely of said truck and having downwardly extending arms adapted to engage said side frames for transmitting lateral forces between said bolster and said side frames, means for resiliently supporting said bolster on said side frames, means including a floating bolster for supporting a railway vehicle on said truck, means for resiliently supporting said floating bolster on said first-mentioned bolster, a lateral restraint device for said floating bolster including brackets on said first-mentioned bolster having vertically 40 extending bearings arranged adjacent the longitudinal and transverse center of said first-mentioned bolster, and means including a downwardly extending element on said floating bolster provided with a roller arranged to engage said bearings for guiding said floating bolster about a vertically movable pivotal center.

3. A railway truck having side frames, a bolster extending transversely of said truck, means for supporting said bolster on said side frames, means for 45 including a floating bolster for supporting a railway vehicle on said truck, means for resiliently supporting said floating bolster on said first-mentioned bolster, a lateral restraint device for said floating bolster including vertically extending bearings secured to said first-mentioned bolster adjacent the longitudinal and transverse center thereof, rocker seats on said floating bolster, means including a downwardly extending element on said floating bolster arranged to engage 50 said bearings for guiding said floating bolster about a vertically movable pivotal center, said downwardly extending element being provided with a rocker arranged in engagement with said rocker seats, and means resiliently biasing said rocker into engagement with said rocker seats for restraining relative lateral movement 55 between said first-mentioned bolster and said floating bolster.

4. A railway truck having side frames, a bolster 60 extending transversely of said truck, means for supporting said bolster on said side frames, means including a floating bolster for supporting a railway vehicle on said truck, means for resiliently supporting said floating bolster on said first-mentioned bolster, a lateral restraint device for said

floating bolster including vertically extending bearings secured to said first-mentioned bolster adjacent the longitudinal and transverse center thereof, rocker seats on said floating bolster, means including a downwardly extending element on said floating bolster arranged to engage said bearings for guiding said floating bolster about a vertically movable pivotal center, said downwardly extending element being provided with a rocker, a link pivotally secured to said 10 rocker, and resilient means engaging said link for biasing said rocker into engagement with said rocker seats and restraining relative lateral movement between said first-mentioned bolster and said floating bolster. 15

5. A railway truck having side frames, a bolster extending transversely of said truck and having downwardly extending arms adapted to engage said side frames for transmitting lateral forces between said bolster and said side frames, means for resiliently supporting said bolster on said side frames, means including a floating bolster for supporting a railway vehicle on said truck, means for resiliently supporting said floating bolster on said first-mentioned bolster, a lateral restraint device for said floating bolster including vertically extending bearings secured to said first-mentioned bolster adjacent the longitudinal and transverse center thereof, means on said floating bolster arranged to engage said bearings for guiding said floating bolster about a vertically movable pivotal center, side bearings on said first-mentioned bolster, and means including complementary side bearings on said floating bolster having rollers arranged to engage said first-mentioned bolster side bearings for transmitting lateral forces therebetween. 30

6. A railway truck having side frames, a bolster extending transversely of said truck and having downwardly extending arms adapted to engage said side frames for transmitting lateral forces between said bolster and said side frames, means for resiliently supporting said bolster on said side frames, means including a floating bolster for supporting a railway vehicle on said truck, means for resiliently supporting said floating bolster on said first-mentioned bolster, means including a longitudinally extending member pivotally connected to said first-mentioned bolster and to one of said side frames for transmitting 45 longitudinal forces therebetween, a lateral restraint device for said floating bolster including brackets on said first-mentioned bolster having vertically extending bearings arranged adjacent the longitudinal and transverse center of said first-mentioned bolster, means including a downwardly extending element on said floating bolster provided with a roller arranged to engage said bearings for guiding said floating bolster about a vertically movable pivotal center, side bearings on said first-mentioned bolster, and means including complementary side bearings on said floating bolster arranged to engage said first-mentioned bolster side bearings for transmitting 50 lateral forces therebetween. 55

7. A railway truck having side frames, a bolster extending transversely of said truck, means for supporting said bolster on said side frames, means including a floating bolster for supporting a railway vehicle on said truck, means for resiliently supporting said floating bolster on said first-mentioned bolster, side bearings on said first-mentioned bolster, side bearings on said floating bolster, each of said floating bolster side bearings including a crank, means for pivotally supporting 70

75

- said crank on said floating bolster, a roller rotatably supported on one arm of said crank, said roller being arranged to engage said first-mentioned bolster side bearings for transmitting lateral forces between said first-mentioned bolster and said floating bolster, and the other arm of said crank being arranged to be biased by said floating bolster resilient supporting means for biasing said roller into engagement with said first-mentioned bolster side bearings.
8. A railway truck having side frames, a bolster extending transversely of said truck, means for supporting said bolster on said side frames, means including a floating bolster for supporting a railway vehicle on said truck, means for resiliently supporting said floating bolster on said first-mentioned bolster, a lateral restraint device for said floating bolster including vertically extending bearings secured to said first-mentioned bolster adjacent the longitudinal and transverse center thereof, means on said floating bolster arranged to engage said bearings for guiding said floating bolster about a vertically movable pivotal center, side bearings on said first-mentioned bolster, means including side bearings pivotally supported on said floating bolster having rollers arranged to engage said first-mentioned bolster side bearings for transmitting lateral forces between said floating bolster and said first-mentioned bolster, said floating bolster side bearings being arranged to engage said floating bolster resilient supporting means for biasing said floating bolster side bearings into engagement with said first-mentioned bolster side bearings.
9. A railway truck having side frames, a bolster extending transversely of said truck and having downwardly extending arms adapted to engage said side frames for transmitting lateral forces between said bolster and said side frames, means including a floating bolster for supporting a railway vehicle on said truck, means for resiliently supporting said floating bolster on said first-mentioned bolster, means including a longitudinally extending member pivotally connected to said first-mentioned bolster and to one of said side frames for transmitting longitudinal forces therebetween, a lateral restraint device for said floating bolster including vertically extending bearings secured to said first-mentioned bolster adjacent the longitudinal and transverse center thereof, means on said floating bolster arranged to engage said bearings for guiding said floating bolster about a vertically movable pivotal center, side bearing means on said first-mentioned bolster and said floating bolster adapted to engage each other for resiliently transmitting lateral forces therebetween.
10. A railway truck having side frames, a bolster extending transversely of said truck and having downwardly extending arms adapted to engage said side frames for transmitting lateral forces between said bolster and said side frames, means including a floating bolster for supporting a railway vehicle on said truck, means for resiliently supporting said floating bolster on said first-mentioned bolster, means including a longitudinally extending member pivotally connected to said first-mentioned bolster and to one of said side frames for transmitting longitudinal forces therebetween, a lateral restraint device for said floating bolster including vertically extending bearings secured to said first-mentioned bolster adjacent the longitudinal and transverse center

thereof, means on said floating bolster arranged to engage said bearings for guiding said floating bolster about a vertically movable pivotal center, side bearings on said first-mentioned bolster, and means including complementary side bearings on said floating bolster arranged to engage said first-mentioned bolster side bearings for transmitting lateral forces therebetween.

11. A railway truck having side frames, a bolster extending transversely of said truck and having downwardly extending arms adapted to engage said side frames for transmitting lateral forces between said bolster and said side frames, means including a floating bolster for supporting a railway vehicle on said truck, means for resiliently supporting said floating bolster on said first-mentioned bolster, means including a longitudinally extending member pivotally connected to said first-mentioned bolster and to one of said side frames for transmitting longitudinal forces therebetween, a lateral restraint device for said floating bolster including vertically extending bearings secured to said first-mentioned bolster adjacent the longitudinal and transverse center thereof, means on said floating bolster arranged to engage said bearings for guiding said floating bolster about a vertically movable pivotal center, side bearings on said first-mentioned bolster, side bearing means pivotally supported on said floating bolster having rollers arranged to engage said first-mentioned bolster side bearings for transmitting lateral forces between said floating bolster and said first-mentioned bolster, said floating bolster side bearing means being arranged to engage said floating bolster resilient supporting means for biasing said floating bolster side bearing means into engagement with said first-mentioned bolster side bearings.

12. A railway truck having side frames, a bolster extending transversely of said truck and having downwardly extending arms adapted to engage said side frames for transmitting lateral forces between said bolster and said side frames, means including a floating bolster for supporting a railway vehicle on said truck, means for resiliently supporting said floating bolster on said first-mentioned bolster, means including a longitudinally extending member pivotally connected to said first-mentioned bolster and to one of said side frames for transmitting longitudinal forces therebetween, a lateral restraint device for said floating bolster including vertically extending bearings secured to said first-mentioned bolster adjacent the longitudinal and transverse center thereof, means on said floating bolster arranged to engage said bearings for guiding said floating bolster about a vertically movable pivotal center, side bearing means on said first-mentioned bolster, side bearing means on said floating bolster, each of said floating bolster side bearings including a crank, means for pivotally supporting said crank on said floating bolster, a roller rotatably supported on one arm of said crank, said roller being arranged to engage one of said first-mentioned bolster side bearings for transmitting lateral forces between said first-mentioned bolster and said floating bolster, and the other arm of said crank being arranged to engage said floating bolster resilient supporting means for biasing said roller into engagement with said first-mentioned bolster side bearing.

OLE K. KJOLSETH.
